UNITED STATES PATENT OFFICE.

LUCIFER J. MOST, OF NEW YORK, N. Y.

ENGRAVING-MACHINE.

1,395,861.

Specification of Letters Patent.

Patented Nov. 1, 1921.

Application filed September 22, 1920. Serial No. 412,036.

To all whom it may concern:

Be it known that I, LUCIFER J. MOST, a citizen of the United States, and resident of the city of New York, in the county of Bronx and State of New York, have invented a certain new and useful Engraving-Machine, of which the following is a specification.

This invention relates to engraving machines, and particularly to machines that are utilized for engraving or chasing the surfaces of mechanical pencils or fountain pens, for the purpose of imparting a roughened surface to such articles, so as to permit a firm hold thereof by the user, and also for the purpose of ornamenting these articles. Heretofore, machines of this character embodied various important disadvantages, in that they were contrived merely to produce a singular predetermined engraved effect upon the cylinder of the pencil, and the machines were inherently capable of producing only a certain class of effects; for the reason that the effect produced depended upon the combined result of the configuration of certain of the machine parts and the manner of their coaction with other machine parts, and the said effect did not constitute any actual counterpart of any machine part *per se*. These machines furthermore operated on but one pencil at one time, required constant manual operation, and were otherwise slow, of low productivity, and deficient in a number of other respects.

The principal object of my invention is to overcome the aforesaid disadvantages, and to provide a simple, inexpensive, conveniently manipulable, automatically operated, highly efficient, and improved engraving machine of increased productivity for the above mentioned purpose.

Another object is to provide a machine for this purpose, wherein the mechanism that executes the chasing operation will be guided and controlled by a master roll, the surface of which itself corresponds to the pattern that is to be engraved upon the pencil cylinders, in contradistinction to the aforesaid machines wherein the effect produced upon the pen or pencil cylinder is a result of the coaction of the machine parts and is therefore difficult of precise predetermination as to character, dimensions, or configuration in the design and construction of the machine.

A further object is to provide this machine with a plurality of interchangeable master rolls, of various patterns, wherewith any one of a series of patterns may be selected for engraving the pencil cylinders.

Other objects and advantages will hereinafter appear.

In the accompanying drawings,—

Figure 1 shows a general plan view of the 65 engraving machine.

Fig. 2 is a side elevation of the machine shown in Fig. 1.

Fig. 3 shows a cross-sectional rear-end elevation of the machine.

Fig. 4 shows a cross-sectional side-elevation of the tracer-device that coöperates with the master-roll of the machine.

Fig. 5 is a front elevation of the tracer device shown in Fig. 4.

Figs. 6 and 7 show a side and end elevation respectively of one of the master rolls of the machine.

Fig. 8 shows a pencil cylinder which has been engraved with the utilization of the 80 master-roll shown in Figs. 6 and 7.

Figs. 9 and 10 show elevations of a master-roll of a different pattern.

Fig. 11 shows a pencil cylinder which has been engraved with the roll shown in Figs. 85 9 and 10.

Figs. 12 and 13 show elevations of a modification of the tracer device, which is particularly adaptable for coöperation with the roll illustrated in Figs. 9, 10.

A drive pulley 1, run by any suitable power belt, not shown, is mounted to revolve loosely upon a drive-shaft 2 which passes through a bearing 3 that forms part of a bracket 4 projecting from a base or bed 5 of the machine, which base is fixed to legs 6 that are in turn secured to any suitable floor, said shaft being adapted to clutch with and unclutch from said pulley, in the manner hereinafter described. The extremity of 100 shaft 2 carries a crank 7, to which is pivotally secured a block 8 that passes through a slotted cross-arm 9, Fig. 2, forming part of a rod 10 fixed to a table 11. Said table and the base 5 are dovetailed together, as shown 105 at 12, Fig. 3, whereby the former is freely slideable over the latter longitudinally, in a direction toward and away from the shaft 2, and hence as the shaft is rotated the crank 7 and block 8 are accordingly revolved, the 110 cross-arm 9 and rod 10 are carried along by said block, and the table 11 is thereby re-

ciprocated forwardly and backwardly along the bed 5. A screw 7^a journaled in a head 7^b of crank 7 and pivotally joined at its end to the block 8 regulates the distance of said 5 block from the shaft 2 and thereby controls the amount of throw of the table 11.

Upon the table 11, near its front end 13, is secured an upright wall 14, by means of bolts 15 passing through flanges 16 thereof 10 and threading into lugs 17 projecting from the sides of the table, and near the opposite end of the table is provided a similar wall 18 forming part thereof. The walls 18, 14 serve as supporting means for series of 15 mounting devices 19, 20 for a plurality of pencil cylinders 21, which, as here shown, consist ordinarily of tubular metallic pencil bodies having conical ends 22. Each of the mounting devices 19 comprises a revolute 20 stud 23 passing through a bearing 24 in the wall 18, and having a knurled conical flange 25 at one extremity thereof and a gear 26 keyed upon its opposite extremity. Each of 25 the devices 20 comprises a shank 27 which passes through a journal 28, wherein it is 30 maintained against rotation by a feather 27^a, whereby it is slidably longitudinally toward and away from the devices 19. One extremity of shank 27 is provided with a small 35 sharp point 29 while its opposite end is provided with a knurled head 30, for convenient manipulation of the device during the mounting and demounting of the pencil cylinders 21. The mounting devices 19 are 40 arranged in a row along the wall 18 and the devices 20 are similarly arranged along the wall 14, with a device 20 directly opposite to and coaxial with each of the devices 19, which opposite two devices thus constitute a 45 coöperating pair, as shown. When it is desired to mount a pencil cylinder 21, the shank 27 is withdrawn backwardly away from its opposite coöperating device 19 and the straight end of the pencil cylinder is then 50 placed over the knurled flange 25, and then the shank 27 is slid back and its point 29 is made to enter into the small opening in the conical extremity of the cylinder 21. A set-screw 31 that passes through the bearing 28 55 is then tightened to press against the shank 27 and lock it against any longitudinal dislocation. The mounting of the cylinder 21 is thus completed, and as the flange 25 bears forcibly against the edge of the cylinder- 60 extremity it compels the cylinder to rotate with the stud 23 upon the rotation of its gear 26, the coöperation of the stationary point 29 of shank 27 with the opposite extremity of the cylinder 21 acting as a bearing 65 ing for the pencil-cylinder.

As here shown, the pencil cylinders 21 when mounted in operative state are six in number and arranged in groups of three at each side of the longitudinal center line of the table 65 11, and between these two groups is located

a master roll 32 which is rotatably mounted by means of a flange 33 forming part of a revoluble stud 34 passing into a central opening in the extremity of the roll, and a dog 33^a projecting from the flange entering 70 an opening 33^b in the roll and said stud passes through a bearing 35 in the wall 18. The opposite extremity of the master-roll 32 is held in pivoted state by means of the point 36 of a centering bar 37 entering a 75 small punch hole in the roll. Said bar is longitudinally slidable in a journal 38 forming part of a post 39 projecting from the extremity of table 11, in which manner the master-roll may be conveniently mounted in 80 operative state and demounted, and when the roll is in mounted state the bar 37 is locked against dislocation by means of the set screw 40 which passes through the journal 38 and is threaded against the bar. 85 Upon the stud 34 is keyed a gear 41 which is similar to the gears 26, and beyond the gear 41 it has keyed thereon a ratchet wheel 42, whereby any rotation of said ratchet causes rotation of the stud 34, gear 41, and the 90 master-roll 32. A train of gears 43, Fig. 3, mounted on studs 43^a secured to the wall 18, transmits the rotation of the gear 41 to each one of the gears 26, whereby any rotation or partial rotation of the stud 34 and master-roll 32 transmits equal and equiangular rotation to the studs 23 and pencil-cylinders 21. 95

Transversely across and above the cylinders 21 and roll 32 is located a carrier-head 44 which is held by a pair of arms 45 that 100 extend therefrom toward the rear of the machine and form part of a rock-shaft 46 which is pivoted, by means of set-screws 47, to the extremities 48 of a pair of brackets 49 that are secured to the rear ends of the sides 105 of the machine-bed 5. In the head 44 is mounted a series of gravers 50, each of which is secured thereto by a set screw 50^a, for the respective pencil-cylinders 21 and each of said gravers is provided with a diamond cutting point 51 that bears down on top of the cylinder 21 directly above its longitudinal center line. On top of the master-roll 32 and directly above its center-line is situated a tracer-wheel 52, Figs. 2, 4, 5, 110 115 which is secured to the head 44 in the manner shown in Fig. 4. To the rear of the base 5 is secured a flat spring 53 which extends therefrom and is bent upwardly in the form of a loop, as shown in Fig. 2. From the rock-shaft 46 extends an arm 54 to which is secured a plate 55 through which threads a thumb-screw 56 that bears against the spring 53, whereby upon threading the screw 56 120 against said spring the arms 45 are forced 125 downwardly and pressure is exerted against the pencil-cylinders 21 by the diamond points 51 of the gravers 50, and the extent of this pressure can be readily regulated by the threading and unthreading of the screw 56. 130

The master-roll 32 is very many times bigger in diameter than the pencil-cylinder 21, and its periphery is provided with a series of grooves or indentations 57, Figs. 6, 7, 5 which in their arrangement and configurations correspond to the pattern, Fig. 8, that is to be engraved upon the pencil-cylinders, the high parts 58 of the roll corresponding to the non-engraved areas 59 of the cylinder 10 and the low portions 57 corresponding to the engraved or chased areas 60 of the cylinder, Fig. 8. As the tracer-wheel 52 rides upon the high areas 58 of the roll 32 it elevates the head 44 and thereby maintains the graver-points 51 in inoperative condition away from the surfaces of the cylinders 21, while when the wheel 52 is in the low indentation areas 57 of the roll 32 it permits the head 44 to drop and the graver points 51 to bear 15 down in operative condition upon the peripheries of the cylinders 21. Assuming, therefore, that the wheel 52 is riding upon the high area 58 of the roll 32 and the table 11 together with all of the parts and mechanism fixed thereto and dependent therewith is reciprocated by the rotation of the drive-shaft 2, then the pencil-cylinders 21 move idly under the graver points 51 and no work is performed upon the cylinder-peripheries; 20 whereas when the table 11 is reciprocated while the tracer wheel is over the low area 57 of the roll 32 then the graver-points 51 bear down forcibly upon the peripheries of the respective pencil-cylinders and cut there- 25 into one of those fine grooves of which each of the chased areas 60, Fig. 8, is composed. In the practical operation of this machine one complete stroke of the table 11, *i. e.*, one forward movement of the table 11 in a direction toward the drive-shaft 2 and its subsequent return is sufficient to cut one of the complete fine grooves of which each chased area 60 is composed.

Under the ratchet 42 is located a pawl 61 45 which is pivoted at 62 to a slide-bar 63, to which is also secured a spring 64 that presses the pawl into mesh with the ratchet. Said bar and the pawl dependent therewith are slidable in a recess 65 in the table 11, in a 50 direction transversely to that of the movement of the table and toward and away from the ratchet 42. As the bar 63 and pawl 42 are slid toward the ratchet 42, the latter has imparted thereto a fractional turn, and upon 55 release of the bar 63 a spring 66, located in a recess thereof and bearing thereagainst and against a portion 67 of the table, forces it away from the ratchet and restores the pawl to initial position. The frictional or angular turn 60 thus imparted to the ratchet 42 is transmitted to the gear 41 and the master-roll 32, and the gear 41 in turn transmits its movement through the gear-train 43 to each of the gears 26 and the pencil-cylinders 21, all 65 of which as well as the roll 32 thereby re-

ceive an equiangular fractional turn which is equal to or sufficient for the distance required between one of the cuts or grooves constituting each chased area 60 and its adjacent cut, in which manner all of the cylinders 21 are thus simultaneously disposed for the reception of a subsequent cut by the graver points upon the succeeding complete stroke of the table 11. To a lug 68 forming part of the base 5 is secured a beveled cam-block 69, by means of a screw 70, and the extremity of the slide-bar 63 is formed into a coöperating beveled-cam 71, whereby as the table 11 completes its return stroke, in a right hand direction as viewed in the drawing, the cam-face 71 abuts against the cam-block 69 and the bar 63 is thereby actuated to impart the required fractional turn to the ratchet 42 and cause the equiangular turns to the master-roll 32 and cylinders 21, to 75 render the latter ready to receive the next cut from the gravers.

In the operation of the machine, the continuous running of the drive-shaft 2 causes constant reciprocation of the table 11, the cams 71, 69, pawl and ratchet 61, 42, and all of the gears operate to feed automatically equiangular partial turns to the roll 32 and the cylinders 21 at the termination of each 80 complete stroke of the table, and the master-roll 32 automatically guides and controls the gravers 50 to carry on the successive cuts upon the cylinders and to simultaneously chase upon all the cylinders a pattern that corresponds to the design of the periphery of 85 the master-roll. In this manner the machine continually operates to carry out automatically its complete function of simultaneously engraving the surfaces of all the pencil-cylinders that are inserted thereinto, until 90 the chasing operation is completed, whereupon the finished cylinders may be conveniently removed and other blank cylinders mounted in their place for receiving the same 95 operation. If desired the master-roll 32 may be also removed and a roll of a different pattern may be conveniently interchanged and mounted in the machine to take its place. It will be noted that while the diameter of 100 the master-roll is greater and its circumferential area is very much larger than that of the pencil-cylinder, yet the strokes performed by the tracer wheel 52 and the gravers 50, which are held by the common carrier-head 44, are identical, as are also the 105 equiangular partial turns simultaneously imparted to the roll and cylinders; and the result thereof is that while a big, strong, inexpensive, and conveniently built structure is afforded in this machine with respect to the 110 master-roll and the tracer-element, the transmission of their coaction to the engraving operation *per se* upon the pencil-cylinders is performed by the identical or same extent 115 of stroke and angular feed, and without the 120 125 130

4
necessity of any complicated transmission or reducing mechanism. In order to shut off and turn on the power conveniently, upon the removal and reloading of the pencil-
5 cylinders into the machine, a clutch 72 is provided comprising a toothed portion 73 upon drive-pulley 1 and a toothed sleeve 74, which is longitudinally shiftable on the drive-shaft 2, by means of the feather 2^a, and
10 revolves with said shaft. A shift-lever 75 fulcrumed at 76 and engaging the sleeve 74 at 77 is guided by a plate 78 projecting from the base 5, whereby swinging of the lever-handle 79 away from the base unclutches the
15 sleeve 74 from the toothed pulley-portion 73 and permits the pulley 1 to run idly upon the shaft 2, while reverse action of the lever clutches the members 73, 74, and thereby the pulley 1 to the shaft 2, and resumes the operation of the machine.

In Figs. 9, 10 is illustrated a master-roll of a different pattern than that shown in Figs. 6, 7 and Fig. 11 shows the chased surface of a pencil-cylinder which is the product of the 25 operation performed with the master-roll in Fig. 9. In this pattern, the elongated groove 80 serves to produce the engraved area 81 upon the cylinder, while the indentations 82 serve to produce the checker-board effect 83 30 upon the cylinder, and it will be evident that an unlimited number of master rolls may be utilized interchangeably in connection with this engraving machine, so as to produce engraved effects upon the cylinders of 35 any pattern or configuration, including even words, monograms, or other such difficult patterns. Where a master-roll is provided with indentations that are short, such as the grooves 82, Fig. 9, it is preferable to utilize 40 a tracer of the type shown in Figs. 12, 13, which comprises a leg 84 having fixed thereto a sharp-pointed, flat tracer-plate 85 which is more suitable than the wheel 52 for dropping into and traversing the entire area of 45 the small indentations.

Figs. 4, 5, illustrate in detail the connection of the tracer with the common carrier-head 44. According to this construction, the tracer-wheel 52 is mounted in a leg 84 having a threaded terminal 86 forming part thereof and threading through a thumb-nut 87 pivotally fitted in the carrier 44. Rotation of the nut 87 adjusts the wheel 52 toward and away from the high surfaces 58 of 55 the master roll 32 until it is regulated to the extent required, whereupon a set-screw 88, passing through the head 44, may be tightened against the leg 84 to secure the wheel 52 in its adjusted position.

60 Variations may be resorted to within the scope of the invention, and portions of the improvements may be used without others.

Having thus described my invention, I claim:—

65 1. An engraving machine having the com-

bination of means for rotatably mounting a plurality of cylinders, an engraved master roll, means for rotatably mounting said roll, a graver for each of said cylinders, a tracer for said roll, a common carrier for said 70 gravers and tracer, means to reciprocate said cylinders and roll longitudinally, means to impart intermittent equiangular rotation to said cylinders and roll, and said roll guiding said tracer to cause said gravers to cut 75 the surfaces of said cylinders in correspondence with its periphery during reciprocation of the cylinders and roll.

2. An engraving machine having the combination of means for rotatably mounting a 80 plurality of cylinders, a rotatably mounted engraved master-roll, a graver for each of said cylinders, a tracer for said roll, means for carrying said tracer and graver, means to reciprocate said cylinders and roll longitudinally relatively to said tracer and gravers, means to impart intermittent equiangular rotation to said cylinders and roll, and said roll guiding said tracer to cause said 85 gravers to cut the surfaces of said cylinders 90 in correspondence with its periphery.

3. An engraving machine having the combination of means for rotatably mounting a plurality of cylinders, a rotatably mounted engraved master roll, a graver for each of 95 said cylinders, a tracer for said roll, means to reciprocate said cylinders and roll longitudinally relatively to said tracer and gravers, means to impart intermittent equiangular rotation to said cylinders and roll, said 100 roll guiding said tracer to cause said gravers to cut the surfaces of said cylinders in correspondence with its periphery, and means to apply pressure of said gravers against said cylinders.

4. An engraving machine having the combination of means for rotatably mounting a plurality of cylinders, a rotatably mounted engraved master-roll, a graver for each of 110 said cylinders, a tracer for said roll, means to reciprocate said cylinders and roll longitudinally relatively to said tracer and gravers, means to impart intermittent equiangular rotation to said cylinders and roll, said 115 roll guiding said tracer to cause said gravers to cut the surfaces of said cylinders in correspondence with its periphery, means to apply pressure of said gravers against said cylinders, and means to regulate said pressure.

5. An engraving machine having the combination of means for rotatably mounting a plurality of cylinders, a rotatably mounted engraved master roll, a graver for each of 125 said cylinders, a tracer for said roll, means to reciprocate said cylinders and roll, means to impart intermittent equiangular rotation to said cylinders and roll, said roll guiding said tracer to cause said gravers to cut the 130 surfaces of said cylinders in correspondence

with its periphery, a common carrier for said gravers and tracer, and an arm extending from said carrier being pivoted to permit the vertical movement of the carrier and 5 gravers.

6. An engraving machine having the combination of means for rotatably mounting a plurality of cylinders, a rotatably mounted engraved master roll, a graver for each of 10 said cylinders, a tracer for said roll, a common carrier for said gravers and tracer, means to reciprocate said cylinder and roll, means to impart intermittent equiangular rotation to said cylinders and roll, said roll 15 guiding said tracer to cause said gravers to cut the surfaces of said cylinders in correspondence with its periphery, an arm extending from said carrier being pivoted to permit the vertical movement of the carrier 20 and gravers, and a spring acting upon said arm to exert pressure of said gravers against said cylinders.

7. An engraving machine having the combination of means for rotatably mounting 25 a plurality of cylinders, a rotatably mounted engraved master roll, a graver for each of said cylinders, a tracer for said roll, a common carrier for said gravers and tracer, means to reciprocate said cylinders and roll, 30 means to impart intermittent equiangular rotation to said cylinders and roll, said roll guiding said tracer to cause said gravers to cut the surfaces of said cylinders in correspondence with its periphery, an arm extending from said carrier being pivoted to permit the vertical movement of the carrier 35 and gravers, a spring acting upon said arm to exert pressure of said gravers against said cylinders, and means to regulate the 40 pressure of said spring.

8. An engraving machine having the combination of means for rotatably mounting a plurality of cylinders, an engraved master roll having a diameter which is several 45 times greater than that of said cylinders, means for rotatably mounting said roll, a graver for each of said cylinders, a tracer for said roll, means for carrying said tracer and gravers, means to reciprocate said 50 tracer and roll longitudinally relatively to said tracer and gravers, means to impart intermittent equiangular rotation to said cylinders and roll, and said roll guiding said tracer to cause said gravers to cut the 55 surfaces of said cylinders in correspondence with its periphery.

9. An engraving machine having the combination of means for rotatably mounting a plurality of cylinders, a master roll having a 60 diameter which is several times greater than that of said cylinders and having in its periphery indentations configured to correspond to the areas that are to be engraved upon said cylinders, means for rotatably mounting said roll, a graver for each 65

of said cylinders, a tracer for said roll, means for carrying said tracer and gravers, means to reciprocate said cylinders and roll longitudinally relatively to said tracer and gravers, means to impart intermittent 70 equiangular rotation to said cylinders and roll, and said roll guiding said tracer whereby its high surfaces actuate said gravers out of effective contact with said cylinders and its low surfaces permit said gravers to cut 75 said cylinders.

10. An engraving machine having the combination of means for rotatably mounting a plurality of cylinders, a master roll having a diameter which is several times 80 greater than that of said cylinders and having in its periphery indentations configured to correspond to the areas that are to be engraved upon said cylinders, means for rotatably mounting said roll, a graver for 85 each of said cylinders, a tracer for said roll, means for carrying said tracer and gravers, means to reciprocate said cylinders and roll longitudinally relatively to said tracer and gravers, means to impart intermittent equiangular 90 rotation to said cylinders and roll, said roll guiding said tracer whereby its high surfaces actuate said gravers out of effective contact with said cylinders and its low surfaces permit said gravers to cut said 95 cylinders, and means to apply pressure of said gravers against said cylinders.

11. An engraving machine having the combination of means for rotatably mounting a plurality of cylinders, a rotatably mounted master roll having a diameter which is several times greater than that of said cylinders and having in its periphery indentations that correspond to the areas 100 that are to be engraved upon said cylinders, a graver for each of said cylinders, a tracer for said roll, means for carrying said tracers and gravers, means to reciprocate said cylinders and roll relatively to said tracer and gravers, means to impart intermittent equiangular 105 rotation to said cylinders and roll, said roll guiding said tracer whereby its high surfaces actuate said gravers out of effective contact with said cylinders and its low surfaces permit said gravers to cut said 110 cylinders, means to apply pressure to said gravers against said cylinders, and means to regulate said pressure.

12. An engraving machine having the combination of means for rotatably mounting a plurality of cylinders, a master roll rotatably mounted and having in its periphery indentations corresponding to the areas that are to be engraved upon said cylinders, a graver for each of said cylinders, a tracer 125 for said roll, means for carrying said tracer and gravers, means to reciprocate said cylinders and roll longitudinally relatively to said tracer and gravers, means to impart intermittent equiangular rotation to said 130

cylinders and roll, and said roll guiding said tracer whereby its high surfaces actuate said gravers out of effective contact with said cylinders and its low surfaces permit said gravers to cut said cylinders.

13. An engraving machine having the combination of means for rotatably mounting a plurality of cylinders, a master roll rotatably mounted and having in its periphery indentations corresponding to the areas that are to be engraved upon said cylinders, a graver for each of said cylinders, a tracer for said roll, means for carrying said tracer and gravers, means to reciprocate said cylinders and roll relatively to said tracer and gravers, means to impart intermittent angular rotation to said cylinders and roll, and said roll guiding said tracer whereby its high surfaces actuate said gravers out of effective contact with said cylinders and its low surfaces permit said gravers to cut said cylinders.

14. An engraving machine having the combination of means for rotatably mounting a cylinder, a rotatably mounted master roll having in its periphery indentations corresponding to the areas that are to be engraved upon the cylinder, a graver for the cylinder, a tracer for said roll, means to reciprocate said cylinder and roll relatively to said tracer and graver, means to impart intermittent angular feed to said cylinder and roll, and said roll guiding said tracer whereby its high and low surfaces actuate said gravers into and out of effective cutting contact with said cylinder.

15. An engraving machine having the combination of means for rotatably mounting a cylinder, a rotatably mounted engraved master roll, a graver for said cylinder, a tracer for said roll, means for carrying said tracer and graver, means to reciprocate said cylinder and roll relatively to said tracer and graver, means to impart intermittent equiangular rotation to said cylinder and roll, and said roll guiding said tracer to cause said graver to cut the surface of said cylinder in correspondence with its periphery.

16. An engraving machine having the combination of means for rotatably mounting a cylinder, a rotatably mounted engraved master roll, a graver for said cylinder, a tracer for said roll, means to reciprocate said cylinder and roll relatively to said tracer and graver, means to impart angular feed to said cylinder and roll, and said roll guiding said tracer to cause said graver to cut the surface of said cylinder in correspondence with its periphery.

17. An engraving machine having the combination with a base, and a drive shaft, of a table adapted to slide upon said base, means to reciprocate said table by the rotation of said shaft, uprights on said table,

means on said uprights for rotatably mounting a plurality of cylinders, a master roll having a diameter which is several times greater than that of said cylinders and having in its periphery indentations corresponding to the areas that are to be engraved upon said cylinders, a spindle on said uprights for rotatably mounting said roll, a graver for each of said cylinders, a tracer for said roll, a common carrier for

70 said gravers and tracer, a pivoted arm fixed to said carrier, a spring acting upon said arm to exert pressure of said gravers against said cylinders, means to regulate the pressure of said spring, a ratchet on said roll-spindle, a bevel cam on said base, a bar slideable on said table having a bevel cam at one end thereof and a pawl, a spring normally pressing said bar and pawl away from said ratchet, said cams colliding at each reciprocation of said table and thereby shifting said bar to cause said pawl to impart a fractional turn to said ratchet and roll, a gear on said roll-spindle receiving said fractional turn, a train of gears transmitting said fractional 80 turn to each of said cylinders, and said roll guiding said tracer whereby its high surfaces actuate said gravers out of effective contact with said cylinders and its low surfaces permit said gravers to cut said cylinders.

18. An engraving machine having the combination with a base, and a drive shaft, of a table adapted to slide upon said base, means to reciprocate said table by the rotation of said shaft, means carried by said table for rotatably mounting a plurality of cylinders, an engraved master roll, means carried by said table for rotatably mounting said roll, a graver for each of said cylinders, 100 a tracer for said roll, a common carrier for said gravers and tracer, a pivoted arm fixed to said carrier, a spring acting upon said arm to exert pressure of said gravers against said cylinders, means to regulate the pressure of said spring, a ratchet on said roll-mounting, a cam on said base, a bar slideable on said table, a pawl on said bar, said bar and cam colliding at each reciprocation of said table and thereby shifting said bar to cause said pawl to impart a fractional turn to said ratchet and roll, a gear receiving said turn, a train of gears transmitting said turn to each of said cylinders, and said roll guiding said tracer to cause said gravers to 110 cut the surfaces of said cylinders in correspondence with its periphery.

19. An engraving machine having the combination with a base, and a drive shaft, of a table adapted to slide upon said base, 125 means to reciprocate said table by the rotation of said shaft, means carried by said table for rotatably mounting a plurality of cylinders, an engraved master roll, means carried by said table for rotatably mounting

- said roll, a graver for each of said cylinders, a tracer for said roll, a common carrier for said gravers and tracer, a ratchet adapted to rotate said roll, a fixed cam, a movable member on said table, a pawl on said member, said member and cam coöperating at each reciprocation of said table and thereby causing said pawl to impart a fractional turn to said ratchet and roll, gears receiving and transmitting said turn to said cylinders, and said roll guiding said tracer to cause said gravers to cut the surfaces of said cylinders in correspondence with its periphery.
20. An engraving machine having the combination with a base, and a drive shaft, of a table upon said base, means to reciprocate said table by the rotation of said shaft, means carried by said table for rotatably mounting a plurality of cylinders, an engraved master roll, means carried by said table for rotatably mounting said roll, a graver for each of said cylinders, a tracer for said roll, means for carrying said tracer and gravers, mechanism operated by the reciprocation of said table to impart a fractional turn to said roll and cylinders, and said roll guiding said tracer to cause said gravers to cut the surfaces of said cylinders in correspondence with its periphery.
- 30 21. An engraving machine having the combination with a base, and a drive shaft, of a table upon said base, means to reciprocate said table by the rotation of said shaft, means carried by said table for rotatably mounting a plurality of cylinders, an engraved master roll, means carried by said table for rotatably mounting said roll, a graver for each of said cylinders, a tracer for said roll, means for carrying said tracer and gravers, mechanism operated by the reciprocation of said table to impart a fractional turn to said roll, means to transmit said turn from said mechanism to said cylinders, and said roll guiding said tracer to cause said gravers to cut the surfaces of said cylinders in correspondence with its periphery.
22. An engraving machine having the combination of means for rotatably mounting a cylinder, a rotatably mounted master roll, a graver for said cylinder, mechanism coacting with said cylinder and said graver,
- means to effect relative reciprocation between said graver and said master roll with the cylinder, means to impart intermittent fractional rotations to said cylinder and roll, and said roll guiding said mechanism to actuate said graver to cut the surface of said cylinder in correspondence with its periphery.
23. An engraving machine for cylinders having the combination of a master roll provided with indentations configurated to correspond to the pattern to be engraved upon the cylinders, means to mount the cylinders, means to transmit fractional turns to said roll and cylinders, gravers for said cylinders, means to reciprocate said roll and cylinders longitudinally relatively to said gravers, and said roll actuating said gravers whereby its high surfaces maintain the gravers out of effective contact with the cylinders and its low surfaces permit said gravers to cut the cylinders.
24. An engraving machine for cylinders having the combination of a master roll provided with indentations configurated to correspond to the pattern to be engraved upon the cylinders, means to mount the cylinders, means to transmit fractional turns to said roll and cylinders, gravers for said cylinders, means to reciprocate said roll and cylinders longitudinally relatively to said gravers, and said roll actuating said gravers to cut the surfaces of said cylinders in correspondence with its indentations.
25. An engraving machine for chasing cylinders having the combination of a master roll having its surface configurated to correspond to the pattern to be engraved upon the cylinders, means to pivotally mount the roll and cylinder, means to transmit fractional turns to said roll and cylinder, a graver for said cylinder, means to reciprocate said roll and cylinder longitudinally relatively to said graver, and said roll actuating said graver to cut the surface of the cylinder in correspondence therewith.
- Signed at the city of New York, in the county of New York, and State of New York, this 20th day of September A. D. 1920.
